CLAIM

The ornamental design for an electronic control apparatus, as shown and described.

DESCRIPTION

FIG. 1 is a perspective view of an electronic control apparatus showing our new design;
 FIG. 2 is a front elevation view thereof;
 FIG. 3 is a left side elevation view thereof;
 FIG. 4 is a top plan view thereof;
 FIG. 5 is a bottom plan view thereof;
 FIG. 6 is a right side elevation thereof; and,
 FIG. 7 is a back elevation view thereof.
